(57) **CLAIM**

The ornamental design for a lock actuator for a playard, as shown and described.

DESCRIPTION

FIG. 1 is a perspective view showing the lock actuator for A playard of my new design;

FIG. 2 is a front elevation view thereof, the rear elevation view being a mirror image of the front elevation view;

FIG. 3 is a bottom view thereof, the top view being a mirror image of the bottom view;

FIG. 4 is a left side elevation view thereof, the right side elevation view being a mirror image of the left side elevation view; and,

FIG. 5 is an enlarged, fragmentary perspective view thereof. The rear view of the lock actuator does not form part of the claimed design. The broken lines show the environment for illustrative purposes only and do not form part of the claimed design.
